UNITED STATES PATENT OFFICE.

WILLIAM C. A. HENRY, OF COLUMBUS, OHIO, ASSIGNOR TO THE B. T. U. COMPANY, OF PITTSBURGH, PENNSYLVANIA, A CORPORATION OF PENNSYLVANIA.

UNDERFEED STOKER.

1,074,118.

Specification of Letters Patent. Patented Sept. 30, 1913.

Application filed April 15, 1912. Serial No. 690,762.

To all whom it may concern:

Be it known that I, WILLIAM C. A. HENRY, a citizen of the United States, residing at Columbus, in the county of Franklin and State of Ohio, have invented certain new and useful Improvements in Underfeed Stokers, of which the following is a specification.

The invention relates to underfeed stokers and particularly to the feed trough construction and the feeding means therein. It has for its primary objects the provision of feed means which will agitate the fuel in the trough and secure its upward movement without an undue forward movement; the provision of a trough construction whereby an upward and lateral feed is promoted at the rear end of the furnace and a proper spreading of the fuel to the corners of the firebox secured; and the provision of means of the character last specified which may be readily varied as to position and upward feeding effect, and which may be readily applied to the trough at the point at which its diameter changes to eliminate the pocket which would otherwise be present at this point. One embodiment of the invention is illustrated in the accompanying drawings, wherein—

Figure 1 is a longitudinal section through a furnace embodying the invention, Fig. 2 is a sectional view through the firebox above the trough, Fig. 3 is a section on the line III—III of Fig. 1, Fig. 4 is a sectional detail view of the filler block which constitutes one feature of the invention, and Fig. 5 is a detail of a modification.

The apparatus is shown as applied to a locomotive firebox, but it will be understood that the invention is applicable to other types of furnaces. Referring to Figs. 1 and 2, the principal elements of the apparatus are illustrated as follows: 1 is the water leg of the firebox; 2 is the front portion of one of the underfeed troughs; 3 is the rear enlarged portion of such underfeed troughs; 4 is a filler block made preferably of cast metal which fits into the front end of the enlarged portion 3 of the trough and abuts at its front end against the rear end of the front portion 2 of the trough; 5 are the grates at the sides of the trough, which grates may be of any approved type and are shown diagrammatically; 6 is the feed chamber at the rear end of the trough, which

chamber receives the fuel to be supplied to the trough; 7 is the main feed plunger or piston working in the feed chamber 6, such plunger being operated from the rock arm 8 in the embodiment of the invention as illustrated; 9, 10, and 11 are what may be termed auxiliary feed pistons, which pistons are actuated to move back and forth by connections a part only of which are shown, and which are immaterial insofar as the present invention is concerned; and 12, 13, and 14 are agitating blocks or members secured to the top of the plungers 9, 10, and 11.

The form of the agitating blocks 12, 13, and 14 constitutes one of the features of my invention. Heretofore the top surfaces of blocks of this character have been inclined downwardly and rearwardly instead of downwardly and forwardly as in the present construction. With such prior art constructions a too great forward feed through the trough was often secured without a sufficient upward feed. It is the purpose of the present invention to provide less forward feed and more upward feed. This has been accomplished by inclining the tops of the agitators downwardly and forwardly, so that the top surfaces of these blocks have substantially no forward feeding effect, but have a component of feeding effect upwardly, and the agitators cut through the fuel and prevent packing, and at the same time cause an upward movement of the fuel to the top of the trough.

The second feature of my invention resides in the provision of what may be termed the filler block, such block being designated by the reference numeral 4 in the particular embodiment of the invention illustrated. The front edge 15 (Fig. 4) of this filler block abuts against the rear end of the portion 2 of the trough, and the interior surface 16 of the filler block corresponds in contour and size with that of the interior of the portion 2 of the trough, so that the interior surface of the filler block constitutes substantially a continuation of the interior surface of the portion 2 of the trough. The rear side edges 17 of the filler block and the rear bottom edge 18 are inclined downwardly and rearwardly as indicated in Figs. 1 and 4, and the block is secured removably in position by means of the studs 19 (Fig. 1). This filler block performs several functions. In the first place it provides a

gradual inclined transition from the large portion of the trough to the small portion thereof, so that the corner or pocket which would otherwise be formed is eliminated 5 and the coal is permitted to feed forwardly from the one portion of the trough to the other, without any substantial resistance. In the second place the inclined surfaces 17 and 18 form a means whereby the coal is 10 given an upward feed through this portion of the trough. This upward feed is desirable inasmuch as there is a tendency in this sort of apparatus for the coal to feed forwardly through the trough and spread out 15 in the forward portions of the furnace, leaving the rear portion of the furnace either partially or wholly uncovered. The upward feed at the rear end of the furnace as occasioned by the filler block causes the 20 coal to work upwardly and then laterally into the corners of the firebox, thus providing these portions of the furnace with the necessary amount of coal and reducing the requirement for hand firing at these portions 25 of the furnace. The making of the block removable also provides a species of adjustment as to this upward and lateral feed at the rear end of the trough, as this upward and lateral movement may be 30 readily varied by substituting for the block in use another block which is either shorter or else has a greater or less degree of inclination at its rear edges. The position and extent of the upward feed can thus be 35 readily regulated and adjusted to suit the requirements of the particular stoker and the particular grade of fuel employed. Other advantages incident to the construction will be apparent to those skilled in the 40 art.

In Fig. 5 a modification of the filler block is shown. In this construction, two separate blocks like the block 20 are employed instead of the single block of Fig. 4, the 45 central portion of the block in Fig. 4 being dispensed with. The feature of the upward feed as induced by the inclined edges is secured the same as in the other form of construction, and it will be understood that my 50 invention comprehends in the broader claims the combination of Fig. 5 as well as that of Fig. 4.

Having thus described my invention and illustrated its use, what I claim as new and desire to secure by Letters Patent is the 55 following:

1. In combination in an underfeed stoker, a forward trough portion, a rear trough portion of larger size, and a filler block open at the top fitting the rear trough portion and abutting the rear end of the front trough portion, the said filler block having its rear edge inclined downwardly to the rear and having substantially the same interior diameter as the said front portion of the trough. 65

2. In combination in an underfeed stoker, a forward trough portion, a rear trough portion of larger size, and a U-shaped removable metal filler block fitting the rear trough portion and abutting the rear end of the 70 front trough portion, the said filler block having its rear edge inclined downwardly to the rear and having substantially the same interior diameter as the forward portion of the trough. 75

3. In combination in an underfeed stoker, a forward trough portion, a rear trough portion of larger size, and a filler block open at the top fitting the rear trough portion and abutting the rear end of the front 80 trough portion, the said filler block having its sides extending substantially to the top of the trough and having its rear edges inclined downwardly to the rear, the said block having substantially the same interior 85 diameter as the forward trough portion.

4. In combination in an underfeed stoker, a forward trough portion, a rear trough portion of larger size, and deflector means fitting against the sides of the larger portion of the trough at its front end and abutting the rear end of the front trough portion, the said deflector means having rearwardly and downwardly inclined rear ends, and the distance between such deflector 95 means being substantially equal to the diameter of the forward trough portion.

In testimony whereof I have hereunto signed my name in the presence of the two subscribed witnesses.

W. C. A. HENRY.
